CARRYING CASE FOR CURRENCY

Application filed January 16, 1931. Serial No. 509,066.

This invention relates to improvements in carrying cases for bank notes and the like.

The invention will be fully understood from the following description taken in connection with the accompanying drawings in which latter—

Fig. 1 is a perspective view of the case;

Fig. 2 is a transverse sectional view taken along the line II—II of Fig. 1 and showing 10 a note in folded position in the case;

Fig. 3 is a perspective view of a detail of the case;

Fig. 4 is a perspective view showing the use of the case;

Fig. 5 is a perspective view of a modified 15 form of the case; and

Fig. 6 is a perspective view showing the use of the modified form of case.

Referring particularly to the drawings, 20 reference numeral 1 designates a body portion and numeral 2 is a flange disposed in spaced relation to the body portion to form a slot 3 extending transversely of the body portion. A cover plate 4 has hinged connection with the body portion rearwardly of the 25 slot 3 cooperating with the body portion to form a receptacle for a plurality of superimposed notes 3'. The slot 3 is adapted to receive the notes folded transversely and around the flange 2. The notes are preferably folded adjacent their middle around the flange and are folded again between a cover plate and body portion as shown in Fig. 2. The flange 2 is formed preferably by folding an extension 6 of the body portion outwardly and rearwardly and extending it 30 through the slot 3 into position 7. The free end of the cover plate overlies the flange 2, and adjoining surfaces of the flange and the free end are substantially parallel thereby forming extended bearing surfaces for gripping the notes. A resilient spring 8 is provided for yieldingly forcing the free end 40 with a self-adjusting pressure against the flange to compress the notes therebetween.

In utilizing the device a plurality of superimposed notes is inserted through the slot 3 and the notes are folded adjacent their middle around the flange to constitute a fold of notes of double thickness, as shown in Fig. 4. The thus folded notes are again folded 50 between the cover plate and body portion forming a fold of notes of quadruple thickness as shown in Fig. 2. The notes are secured in this position within the case by the spring-pressed cover plate. In order to remove a note from the device the cover plate is elevated and the notes are drawn out of the case to the position illustrated in Fig. 4. The spring-pressed cover plate is then allowed to close against the notes, compressing 55 them between the free end of the cover plate and the flange over an extended area with a continuously applied yieldable pressure which is adjusted to effect a grip of predetermined amount. A particular note to be extracted is then grasped at one end by the operative, and is withdrawn from the case, as in Fig. 4, preferably by a quick pull until the note is entirely removed from the case. 60 In this operation the remaining notes remain in the case without substantial shifting of their position. The notes remaining in the case are then folded back against themselves between the cover plate and body portion as shown in Fig. 2, and retained under pressure of the cover plate. 65

By the construction described, a container or carrying case for bank notes and the like is provided in which a plurality of notes is retained folded against themselves in superimposed relation. The notes are threaded through the container and therefore are at all times attached or held to the container. Any one of the notes can be extracted as desired rapidly and without displacement of the remaining notes in the case which remaining notes are positively retained in the case, being folded through the slot and around the flange during the extraction operation, and secured 80 85 90 95

under the self-adjusting pressure of the cover plate against the flange.

Referring particularly to Figs. 5 and 6, a modified form of the device is shown comprising a body portion 10 which can be formed of flexible material such as leather. Cover plate 11 and end 12 are flexibly attached to the body portion and can be folded over the body portion in overlapping relation and secured by snap button 13. A separate inflexible member comprising a base 14 is provided attached to the body portion 10 but having its flange 15 offset laterally. Flange 15 is substantially flat and forms an extended area substantially parallel to base 14. The base 14 is secured to the flexible body portion 10 as by rivets in position to be overlapped by the cover plate 11 and end 12. Flange 15 is disposed in spaced relation to the base 14 to form a slot 18 extending transversely of the base. The slot is of sufficient length to receive a plurality of notes folded adjacent their middle around the flange 15.

In utilizing this form of the device to extract a given note from a plurality of notes disposed in the case, the cover plate 11 and end 12 are opened to permit the notes to be drawn out to the position shown in Fig. 6. The cover 11 is then pressed yieldably by the hand of the operative against the bend of the notes overlying extended flange 15, this pressure acting in the same capacity as the spring member in the first mentioned device. The end of the note to be extracted is then grasped by the other hand of the operative who draws the note from the case without displacement of the notes remaining in the case.

Various changes may be made within the scope of the appended claims in which it is desired to claim all novelty inherent in the invention as broadly as the prior art permits.

We claim:

1. A case for bank notes and the like, comprising a body portion, a flange disposed in spaced relation to the body portion to form a slot extending transversely of the body portion, and a cover plate having hinged connection with the body portion rearwardly of the slot cooperating with the body portion to form a receptacle for a plurality of superimposed notes, the slot being adapted to receive the notes folded transversely through the slot and around the flange, the free end of the cover plate overlying the flange, the adjoining surfaces of the flange and said free end being substantially parallel and constituting extended bearing surfaces for gripping the notes.

2. A case for bank notes and the like, comprising a body portion, a flange disposed in spaced relation to the body portion to form a slot extending transversely of the body portion, a cover plate having hinged connection with the body portion rearwardly of the slot cooperating with the body portion to form a

receptacle for a plurality of superimposed notes, the slot being adapted to receive the notes folded transversely through the slot and around the flange, the free end of the cover plate overlying the flange, the adjoining surfaces of the flange and said free end being substantially parallel and constituting extended bearing surfaces for gripping the notes, and means yieldably forcing the free end and flange against each other to compress the portion of the notes therebetween.
